United States Patent Office

Des. 188,047

Patented May 31, 1960

188,047

BARBER CHAIR OR SIMILAR ARTICLE

Courtney A. Leubner, River Forest, Ill., assignor to Emil J. Paidar Company, Chicago, Ill., a corporation of Illinois

Filed Aug. 29, 1958, Ser. No. 52,444

Term of patent 14 years

(Cl. D15—3)

Figure 1 is a perspective view taken from the front of the chair embodying the features of design of the present invention; and

I claim:

The ornamental design for a barber chair or similar article, as shown.
